MAGAZINE FOR RAZOR BLADES

Zernach Auerbach, New York, N. Y.

Original application April 7, 1942, Serial No. 437,954. Divided and this application August 21, 1943, Serial No. 499,496

5 Claims. (Cl. 30—40)

1

This invention relates to improvements in magazines safety razor blades.

This application is a division of Patent No. 2,327,388, issued August 24, 1943.

Briefly, it is an object of my invention to provide for a magazine for razor blades which is inexpensive to manufacture, simple in construction and easy to manipulate.

More particularly, an object of my invention is to provide an improved magazine for double-edged razor blades which provides for automatically positioning the blades and for fitting the blades into a razor and for retaining the blades in a central position within the magazine so that the cutting edges are out of contact with the magazine walls.

A further object of my invention is to provide a magazine for double-edged safety razor blades which will assure the feeding of a single blade from the magazine into a razor.

For a fuller understanding of the nature and objects of my invention, reference is had to the following detailed description in connection with the accompanying drawings, in which:

Fig. 1 is a side view of a magazine showing a razor head in position upon same and showing the upper blade being fed into the razor and ejecting the used blade from the razor.

Fig. 2 is a top view of the magazine shown in Fig. 1.

Fig. 3 is a section taken through line 3—3 of Fig. 2.

Fig. 4 is a front view of the magazine shown in Figs. 1, 2, and 3, with the front wall removed.

Fig. 5 is a perspective view of a modified double-edged safety razor blade magazine.

Fig. 6 is a longitudinal section of the magazine shown in Fig. 5.

Fig. 7 is a top view of the blade pusher in relation to a blade with the blade partly broken away.

Fig. 8 is a plan view of the blank of the magazine shown in Figs. 5 and 6.

Fig. 9 is a perspective view showing the magazine shown in Fig. 5 in position with a spreadable razor.

Referring to the drawings, Figs. 1—4, inclusive, numeral 99 is a magazine for double-edged razor blades comprising a bottom 100, sides 101—101, vertical members 102—102, flanges 103—103 bent horizontally from the channel members 102—102, ribs 104—104 pressed into the flanges 103—103, all of the above being fashioned from one piece of material. The front part of vertical members 102—102 is curved inwardly as shown at 105, and the front part of each flange 103—103 is curved upwardly, as shown at 106. Between the sides 101—101 and 102—102, there are longitudinal channels 107. Between the sides 101—101 and bottom 100 there is a stationary sloping back 108. At the front of magazine 99 there is a vertical

2

movable front wall 109 riding in grooves in sides 101 and sloping in the same direction as the back 108 and parallel thereto. A spring 110 bent upward from the same material as bottom 100 retains front wall 109 under upward pressure. The top of wall 109 has a flange 111 bent forward and a small projection 112 bent rearwardly at the center. Bottom 100 has a spring 113 for retaining a stack of blades 114 under upward pressure. 10 In order to use magazine 99 in connection with a razor, the razor head is placed with the head downward upon flange 111 and pressed down. This causes the front wall 109 to descend at the same time causing small projection 112 to depress 15 the stack of blades 114 with the exception of the uppermost blade 115. As the razor head 50 is thus pressed downward upon flange 111, it is also moved horizontally into the magazine 99. The guards of the razor enter channels 107—107 because of the inwardly curved members shown at 105 which causes the split razor head 50 to spread apart gradually since the distance between channels 107—107 is greater than the distance between the guards of the razor. The platform of 20 25 30 35 40 45 50 55 60

the razor enters the space between the long ribs 104—104. The downward movement of the front wall 109 creates a clearance for the entrance of the cap of the razor, leaving the uppermost blade 115 ready to contact the used blade 116 in the razor head. As the razor head is moved into the magazine 99, the uppermost blade 115 contacts the used blade 116 in the razor head and ejects it while the uppermost blade 115 enters the razor head.

Upon withdrawing the razor from the magazine 99, the razor head contracts and automatically positions the blade firmly in the razor head ready for use. The blade below blade 115 which is now within the razor becomes the top blade and is retained by projection 112 and rests against ribs 104 under upward pressure.

Spring 113 is attached to the bottom 100 of the magazine so that it constantly maintains upward pressure upon the stack of blades 114, so that the uppermost blade is always in position to be fed into the razor in the manner aforesaid. It should be noticed that the stack of blades 114 is stepped by the angular position of the front and rear walls 109 and 108, respectively.

The stack of blades 114 is retained in the magazine by the upward pressure of the spring so that the cutting edges of the blades do not at any time contact the side walls 101—101 of the magazine since the magazine is much wider than the blades. When the razor head enters the magazine, the razor head is spread apart so that the cutting edges of the blade are not marred upon entrance into the razor head. When the razor head is removed from the magazine, the razor

head contracts gripping and positioning the blade in shaving position.

Referring to Figs. 5 to 8, inclusive, numeral 116 represents a modified magazine for double-edged razor blades, comprising a bottom 117, sides 118—118, a back 119, a front 120, a top 121 and a vertical tongue 122 located in the center of front 120. Front 120 has a horizontal opening 123 near the top 121. Top 121 has a longitudinal opening 124 along the longitudinal medial line. Finger piece 125 attached to pusher 126 through the opening 124 slides along the top 121. A spring 136 is attached to the bottom 117 on the inside of the magazine to hold a stack of blades 135 under upward pressure. The uppermost blade 127 of the stack of blades 135 fits within the recess 128 of pusher 126, while extensions 129—129 embrace the uppermost blade 127 to assure movement of blade 127 along the medial line of the magazine, preventing the cutting edges from touching the inside walls of sides 118—118.

When the vertical tongue 122 of the magazine shown in Fig. 5 is projected between the flanges of the spreadable razor, shown in Fig. 9, the complementary parts of the blade platform of the razor are forced away from each other to an extent whereby the distance between the pair of abutments on one plate and the pair of abutments on the other plate is greater than the width of the blade to be used in the razor, so that a blade can be ejected into the blade confining space without hindrance from the abutments. When the vertical tongue 122 is withdrawn, the complementary parts come together causing the blade to be gripped between the opposing pair of abutments and, therefore, rigidly held in position for shaving.

Referring to Fig. 8, numeral 130 is a blank for the upper part of the magazine shown in Figs. 5 and 6 comprising the back 119, sides 118—118, front 120—120, tongue 122, top 121 and cutouts 131 to form opening 124 shown in Fig. 5. Top portions 121 are cut horizontally at 132 and vertically at 133 adjacent the back 119 and extend to the center of back 119 forming an extension beyond the back. Top 121 is bent at 134 which is slightly above sides 118—118 to form front opening 123 and rear opening 135.

It is obvious that various changes and modifications may be made in the details of construction without departing from the general spirit of the invention, as set forth in the appended claims.

I claim:

1. A magazine for inserting a double-edged razor blade into a split head razor, opposed channels upon said magazine, curved members, opposed flanges bent horizontally from said channels leaving an opening between said flanges, inwardly curved vertical opposed members, longitudinal depressed ribs in said flanges extending a short distance from the front and rear ends of said flanges to create a space between said flanges and the uppermost blade in said magazine, a sloped back for staggering said blades, a vertically movable front parallel to said back, and a spring for maintaining said front under upward pressure.

2. A magazine for inserting a double-edged razor blade into a split head razor, opposed channels upon said magazine, curved members, opposed flanges bent horizontally from said channels leaving an opening between said flanges, inwardly curved vertical opposed members, longi-

tudinal depressed ribs in said flanges extending a short distance from the front and rear ends of said flanges to create a space between said flanges and the uppermost blade in said magazine, a sloped back for staggering said blades, a vertically movable front parallel to said back, a spring for maintaining said front under upward pressure, and a platform projecting outwardly from said front wall to depress said front wall.

3. A magazine for inserting a double-edged razor blade into a split head razor, opposed channels upon said magazine, curved members, opposed flanges bent horizontally from said channels leaving an opening between said flanges, inwardly curved vertical opposed members, longitudinal depressed ribs in said flanges extending a short distance from the front and rear ends of said flanges to create a space between said flanges and the uppermost blade in said magazine, a sloped back, a vertically movable front parallel to said back, a spring for maintaining said front under upward pressure, a platform projecting outwardly from said front wall to depress said front wall, and a finger projecting inwardly from said front wall for singly fingering blades within said magazine.

4. A magazine for inserting a double-edged razor blade into a split head razor, opposed channels upon said magazines, curved members, opposed flanges bent horizontally from said channels leaving an opening between said flanges, inwardly curved vertical opposed members, longitudinal depressed ribs in said flanges extending a short distance from the front and rear ends of said flanges to create a space between said flanges and the uppermost blade in said magazine, a sloped back, a vertically movable front parallel to said back, a spring for maintaining said front under upward pressure, a platform projecting outwardly from said front wall to depress said front wall, and a finger projecting inwardly from said front wall for singly fingering blades within said magazine.

5. A magazine for double edged razor blades comprising a bottom, opposed sides, a sloped back for staggering said blades, top longitudinal ridges forming longitudinal channels beneath said ridges, opposed flanges extending horizontally from said ridges, said flanges having front rounded edges, a longitudinal opening between said flanges, depressed longitudinal ribs along the center of said flanges spaced a short distance from the front and rear of said flanges, a front for said magazine, a vertically movable tongue at the front of said magazine, an inward projection from said tongue slightly below said flanges for singly releasing blades, and a spring at the bottom of said magazine for maintaining an upward pressure upon said blades.
